UNITED STATES PATENT OFFICE.

JOHN HALBRITTER, OF BOSTON, MASSACHUSETTS, ASSIGNOR TO WALWORTH MANUFACTURING COMPANY, OF BOSTON, MASSACHUSETTS, A CORPORATION OF MASSACHUSETTS.

WRENCH.

1,358,078.

Specification of Letters Patent.

Patented Nov. 9, 1920.

Application filed May 19, 1920. Serial No. 382,548.

To all whom it may concern:

Be it known that I, JOHN HALBRITTER, of Boston, in the county of Suffolk and State of Massachusetts, a citizen of the United States, have invented a new and useful Improvement in Wrenches, of which the following is a full, clear, and exact description, reference being had to the accompanying drawings, forming a part of this specification, in explaining its nature.

The present invention relates to an improvement in wrenches of that type in which a chain or other flexible member, passed around the work, acts as one of the operating parts.

The invention is essentially an improvement upon the wrench shown and described in Letters Patent of the United States No. 802,187, of October 17, 1905.

The object of the invention is to provide whereby the wrench may be operated for turning the work in reverse directions without the renewal or readjustment of the chain or flexible member. A further object is to provide whereby the parts of the wrench may be easily assembled or disassembled or the wearing parts easily replaced as occasion may require.

The invention can best be seen and understood by reference to the drawings, in which—

Figure 1 is a side elevation of the wrench occupying an engaging position applied to a piece of pipe, the handle of the wrench being shown only in part.

Fig. 2 is a plan of the same.

Fig. 3 is an interior side elevation of one of the sides or cheeks of the head of the wrench.

Fig. 4 is the same as Fig. 1 excepting that one of the sides or cheeks of the wrench is removed and certain of the connecting parts are shown in cross section. The figure illustrates the engaging position assumed by the operating parts of the wrench for turning the pipe or work in one direction.

Fig. 5 is the same as Fig. 4 excepting that the operating parts have been moved to assume a changed engaging position for turning the pipe or work in a reverse direction to that obtained by the arrangement shown in Fig. 4, and

Fig. 6 is a section taken on the line 6—6 of Fig. 5.

Referring to the drawings:—

1 represents the head of the wrench, 2 the lever with operating handle, 3 the flexible member or chain and 4 the work.

The head 1 of the wrench comprises spaced sides or cheeks 5, 5, respectively. Projecting from the inner faces of these sides are aligned butts 6, 6, with meeting ends which preferably fit into one another. These butts act to space the sides and when combined form a bearing with which the end of the lever has engagement, as will later be explained. The sides are fastened by means of a pin or bolt 7 passed through them and through the respective butts and headed against the outer faces of the sides. The outer ends of the respective sides or cheeks engage the work, and for effecting such engagement the ends are made substantially V-shaped with opposing jaws 8 and 9, respectively, provided with transverse teeth. Adjacent their inner or rear edges the sides are provided with longitudinal slots 10. Contained to run within these slots and extending through them is a crosspin or bolt 11 on which the inner end 12 of the lever is pivotally mounted. The bolt 11 is held against lateral displacement and otherwise retained to be movable freely within the slots by fitting the bolt at one end with a head 13 and a washer 15 interposed between it and the outer face of one of the sides of the head adjacent the slot in it. At the opposite end the bolt is provided with a nut 14 and washer 15' interposed between it and the other side of the head adjacent the slot in it. The nut 14 fits upon a contracted portion of the bolt extending forward from a shoulder 16 on the bolt which lies slightly outside the slot so that when the nut is tightened it and the interposed washer 15' will tighten against the shoulder 16, the parts being thereby made secure, but enabling the bolt to be movable freely within the slots in the head.

The inner end 12 of the lever is so reduced as to leave a space on either side between it and the inner faces of the respective sides 5, 5 of the head between which it is interposed. Located within the spaces thus provided and pivotally secured to the body of the pin or bolt 11 are spaced links 17, 17. These links extend outwardly by the inner faces of the respective sides and to the outer ends thereof is connected the inner

end of the flexible member or chain 3. The connection between the chain and the links is effected by providing the innermost set of links 19 of the chain with a crosspin 20 which extends through the links 17, a suitable spacing member 21 being interposed between the links of the chain. The crosspin 20 extends beyond the outer faces or sides of the respective links 17 and the opposite ends thereof are contained within sockets 23 formed within the respective sides of the head (see Fig. 3). These sockets are of sufficient size to enable the outer ends of the links 17 to have more or less freedom of movement, the walls thereof acting to prevent the links from falling away from between the respective sides of the head when the links are in connection with the pin 11. A portion of the sockets 23 lie beyond the outer ends of the links 17 when connected to the pin 11 and these extended portions of the sockets are open to the edges of the respective sides at points 24, thereby enabling the crosspin 20 to be slipped in or out of the sockets when the links 17 are disconnected from the pin 11 by the withdrawal of the pin.

The chain 3 is of the type customarily used with wrenches of the present type. Its links are connected by crosspins 26 which project laterally from the respective sides of the head and after the chain has been passed around the work are adapted to catch behind ears 27 projecting from the inner faces of the respective sides of the head adjacent the outer end thereof.

The lever 2 is provided with a handle 28 more or less extended in length and of which a portion only is shown in the drawings. The inner or power-applying portion 12 of the lever or that portion thereof lying beyond the pin 11 on which the lever fulcrums is provided with separate rounding cam edges 30, 31, respectively. These edges are so disposed that either one or the other will be brought into engagement with the butts 6, 6 of the head depending as the handle 28 of the lever is moved in one direction or the other and with the effect in either instance of retracting the crosspin 11 in the slots 10, or, in other words, of moving this pin in the direction of the rear end of the head.

The disposition of the cams is also such that the pin 11 will have been moved to engage the rear ends of the slots 10 before the cams have completed their operation for retracting this pin, thereby preventing the cams leaving their bearing as the lever is turned and maintaining the cams always in proper operative position to engage their bearing and the inner end of the lever always within the head.

Between its cams 30, 31 the inner end 12 of the lever is provided with a depressed or

sunken portion 32. This portion is centrally disposed and of sufficient depth and extent to throw the inner end of the lever out of engagement with the bearing 6, 6 when the lever is occupying a neutral position and enabling it and the pin 11, on which it is fulcrumed, to move forward in the direction of the bearing until the pin engages the forward ends of the slots 10 in the sides or approaches such engagement. The surfaces presented by the cams 30, 31 and sunken portion 32 are preferably continuous, the surfaces of the cams merging into that of the sunken portion and extending outwardly therefrom in opposite directions.

The operation is as follows: The jaws of the wrench are brought to bear against the side of the work or pipe and the lever then turned to a neutral position when the sunken face portion 32 thereof engages the bearing 6 and the pin 11, on which the lever fulcrums, is moved forward in the slots 10 as above explained. The chain is then wrapped tightly around the work and one of its pins 26 placed behind the ears 27 on the head.

Assuming that the work is to be turned clockwise, the handle of the lever is then thrown down. Thereupon the cam 30 will be brought into engagement with the bearing 6, 6 with the combined effect of projecting the head and throwing the teeth 8 thereof into engagement with the work and at the same time, through retraction of the pin 11 and the links 17 carried by this pin, tightening the chain against the work, when the work may be turned by further depression of the lever (see Fig. 4).

The position of the wrench may then be shifted upon the work simply by elevating the handle of the wrench sufficiently to loosen the grip of the jaws and chain upon it when the shifting may be effected and afterward the operation of turning the work may be continued the same as before.

Assuming now that it is desired to turn the work counterclockwise, then the lever is elevated until the cam 31, through engagement with the bearing 6, 6, operates to tighten the teeth and chain against the work through the projection of the head and retraction of the pin 11 effecting draw upon the chain. As the lever is elevated it is the teeth on the jaw 9 of the wrench which are thrown into engagement with the work and the counterclockwise movement or rotation of the work is effected simply by a further elevation of the lever handle after the tightening of the engaging parts with the work has been effected as aforesaid. During such movement or at any phase of the movement the wrench may be shifted upon the work and a new grip taken simply by lowering the handle of the wrench until

the gripping parts have been released sufficiently to enable the wrench to assume a changed position, when the operation may be continued simply by a further elevation 5 of the handle (see Fig. 5).

It is to be noted that during the shifting of the wrench upon the work for the purpose of obtaining a fresh grip and especially during the operation of the wrench for im- 10 parting a reverse movement to the work, it is unnecessary to rewrap the chain around the work or readjust it in any way, the shifting of the wrench on the work or the reverse turning thereof being effected simply 15 by manipulation of the handle.

Having thus fully described my invention, I claim and desire to secure by Letters Patent of the United States:—

1. A wrench of the type specified comprising a head having work-engaging jaws oppositely arranged, said head having also a stationary bearing, a lever and fulcrum member for said lever, means for loosely mounting said fulcrum member on said head 25 whereby it may be movable toward or away from said stationary bearing, said lever having separate cams arranged to severally engage said bearing depending upon the direction the lever is turned, said cams and 30 stationary bearing occupying such relation to one another that the engagement of either of the cams with said stationary bearing will exert pressure to project said head and retract said fulcrum member, a flexible member 35 connected at one end of said fulcrum member and attachable to said head, and means for securing such attachment.

2. A wrench of the type specified comprising a head having work-engaging jaws oppositely arranged, said head having also a stationary bearing, a lever and fulcrum member for said lever, means for loosely mounting said fulcrum member on said head whereby it may be movable with relation to 45 said stationary bearing toward or away from the same, said lever having separate cams arranged to severally engage said bearing as the lever is moved in reverse directions or occupy a position out of engagement with 50 said bearing depending upon the set position of said lever, said lever and stationary bearing occupying also such relationship that when the cams are out of engagement with said stationary bearing the fulcrum member 55 for the lever will be freely movable on said head toward or away from said bearing and when either of the cams are brought into engagement with the stationary bearing force will be exerted by the lever 60 to project the head and retract said fulcrum member, a flexible member connected at one end to said fulcrum member and attachable to said head, and means for securing such attachment.

3. A wrench of the type specified comprising

ing a head having connected spaced sides with work-engaging jaws oppositely arranged, said head having also a stationary bearing between its sides, a lever and fulcrum member for said lever, means for 70 loosely mounting said fulcrum member on said head whereby it and said lever may be movable toward or away from said stationary bearing, said lever having separate cams arranged to severally engage said stationary 75 bearing depending as the lever is turned in reverse directions or occupy disengaging positions with relation thereto, said cams and stationary bearing being relatively arranged whereby the engagement of either 80 of the cams with said bearing will exert force acting to project said head and retract said fulcrum member, a flexible member connected at one end to said fulcrum member and attachable to said head, and means for 85 securing such attachment.

4. A wrench of the type specified comprising a head having a work-engaging jaw and a stationary bearing, a lever and fulcrum member for said lever, means for loosely 90 mounting said fulcrum member on said head whereby it may be movable toward or away from said stationary bearing, said lever having a cam arranged to engage said bearing as the lever is turned, said cam and 95 stationary bearing occupying such relationship that the engagement of the cam with said bearing will exert pressure to project the head and retract said fulcrum member, a flexible member connected at one end to 100 said fulcrum member and attachable to said head, and means for securing such attachment.

5. A wrench of the type specified comprising a head having connected spaced sides 105 with work-engaging jaws and an interposed stationary bearing, a lever and fulcrum member for said lever, means for loosely mounting the fulcrum member on the sides of said head whereby it may be 110 movable toward and away from the stationary bearing, said lever having a cam arranged to engage said bearing as the lever is turned and thereby exert pressure to project the head and retract said fulcrum member 115 120, a flexible member attachable to said head, means for securing such attachment, and means whereby said flexible member may be secured to said fulcrum member inside said head.

6. A wrench of the type specified comprising a head having connected spaced sides with work-engaging jaws and an interposed stationary bearing, a lever and fulcrum member for said lever, means for loosely 125 mounting the fulcrum member on the sides of said head whereby it may be movable toward and away from the stationary bearing, said lever having a cam arranged to engage said bearing as the lever is turned 130

and thereby exert pressure to project the head and retract said fulcrum member, a set of spaced links mounted upon said fulcrum member inside said head, a flexible member connected to said links and attachable to said head, means for connecting the flexible member to said links, and means for attaching the flexible member to said head.

7. A wrench of the type specified comprising a head having connected spaced sides with work-engaging jaws and an interposed stationary bearing, said sides being provided with sockets on the inner sides thereof, a lever and fulcrum member for said lever, means for loosely mounting the fulcrum member on the sides of said head whereby it may be movable toward and away from the stationary bearing, said lever having a cam arranged to engage said bearing as the lever is turned and thereby exert pressure to project the head and retract said fulcrum member, a set of spaced links mounted upon said fulcrum member inside said head, a flexible member, a crosspin connecting said flexible member to said links and extending at opposite ends thereof to be contained within the sockets in the inner sides of said head, said flexible member being attachable to said head, and means for securing such attachment.

8. A wrench of the type specified comprising a head having connected spaced sides with work-engaging jaws and an interposed stationary bearing, said sides being provided with sockets on the inner sides thereof, said sockets having openings into the edges of said sides, a lever and fulcrum member for said lever, means for releasably and loosely mounting the fulcrum member on the sides of said head whereby it may be movable toward and away from the stationary bearing, said lever having a cam arranged to engage said bearing as the lever is turned and thereby exert pressure to project the head and retract the fulcrum member, a set of spaced links releasably mounted upon the fulcrum member inside the head, a flexible member, a crosspin connecting said flexible member to said links and extending at opposite ends thereof to be contained within the sockets in the inner sides of said head below the openings out of the same and be releasable from said sockets through said openings when the links are released from the fulcrum member, said flexible member being attachable to said head, and means for securing such attachment.

9. A wrench of the type specified comprising a head having connected spaced sides with work-engaging jaws oppositely arranged, said head having also a stationary bearing interposed between said sides, a

lever and fulcrum member for said lever, means for loosely mounting said fulcrum member on the sides of said head whereby it may be movable toward and away from said stationary bearing, said lever having separate cams arranged to severally engage said bearing as the lever is moved in reverse directions or occupy positions out of engagement with said bearing depending upon the set position of said lever, said cams and stationary bearing being also relatively arranged whereby the engagement of the cams with said bearing will exert force for projecting said head and retracting said fulcrum member, a set of spaced links connected to said fulcrum member inside said head, a flexible member, means for connecting the same to said links, said flexible member being attachable to said head, and means for securing the attachment of the flexible member to said head.

10. A wrench of the type specified comprising a head having work-engaging jaws oppositely arranged, a lever and fulcrum member for said lever, means for loosely mounting said fulcrum member on said head whereby it may be movable thereon, means whereby pressure may be exerted to project said head and retract said fulcrum member when the lever is moved in reverse directions, a flexible member connected at one end to said fulcrum member to be movable therewith, said flexible member being attachable to said head, and means for securing such attachment.

11. A wrench of the type specified comprising a head having a work-engaging jaw, a lever and fulcrum member for said lever, means for loosely mounting said fulcrum member on said head whereby said head may be projected and said fulcrum member retracted when said lever is turned, a flexible member connected at one end to said fulcrum member and attachable to said head, and means for securing such attachment.

12. A wrench of the type specified comprising a head having connected spaced sides with work-engaging jaws, a lever and fulcrum member for said lever, means for loosely mounting the fulcrum member on the sides of said head to be movable thereon, means whereby said head may be projected and said fulcrum member retracted on turning said lever, a set of spaced links mounted upon said fulcrum member inside said head, a flexible member connected to said links and attachable to said head, means for connecting the flexible member to said links and means for attaching the flexible member to said head.

JOHN HALBRITTER.
